RAILWAY TRAFFIC CONTROLLING
APPARATUS

Ronald A. McCann, Swissvale, and Henry S. Young, Wilkinsburg, Pa., assignors to The Union Switch & Signal Company, Swissvale, Pa., a corporation of Pennsylvania

Application February 19, 1931, Serial No. 516,912
Renewed August 8, 1932

9 Claims. (Cl. 246—3)

Our invention relates to railway traffic controlling apparatus, and particularly to apparatus of the type involving the control of a railway switch together with its associated signals from a distant point, such as a despatcher's office. One feature of our invention is the provision of novel and useful means for checking the approach locking of the switch in systems of this kind.

10 We will describe one form of apparatus embodying our invention, and will then point out the novel features thereof in claims.

The accompanying drawing is a diagrammatic view showing one form of apparatus embodying our invention.

Referring to the drawing, the reference characters 1 and 2 designate the track rails of a stretch of railway track which we shall call the "main" track. These rails are divided by the usual insulating rail joints 3 to form three track sections L2T, 1T and R2T of which the section 1T may be termed a "detector" track section and the sections L2T and R2T may be termed "approach" track sections. Located in the detector track section 1T is a switch SW which when reversed diverts traffic from the main track into a siding PS.

Each track section is provided with the usual track circuit. In connection with the two approach track sections L2T and R2T, the track circuit includes a battery 4 connected across the rails at one end of the section and a track relay designated by the reference character TR plus an exponent corresponding to the section connected across the rails at the opposite end of the section. The track circuit for the section 1T includes a track battery 4 connected across the rails 5 and 6 of the siding, which rails are connected to the rails 1 and 2 respectively of the main track at the fouling point, and a track relay 1TR connected across the rails at the right-hand end of the section 1T.

The switch SW is operated by any standard type of switch machine indicated in the drawing by a symbol and designated by the reference character SM. As the operating circuits of the switch machine form no part of our invention, they are omitted from the drawing for the sake of clearness, it being understood that they may be any one of the several types in general use. The control of the switch machine SM is preferably by means of a direct current polarized relay W. With the relay W energized with normal polarity of current, then its polarized armatures are moved to a normal position, which

is the left-hand position in the drawing, to close the normal operating circuits (not shown) of the switch machine SM. With the relay W energized with reverse polarity of current, its polarized armatures are shifted to a reverse position 60 that is the right-hand position in the drawing, to close the reverse operating circuits of the switch machine SM. The relay W is controlled in turn preferably by means of code relays 6Y and 6X which themselves are controlled from 65 some distant point such as a despatcher's office. With the normal code relay 6X selected and its armatures 7 and 8 raised to engage their front contacts, current is supplied to the relay W from the positive terminal B of a convenient source of 70 power, not shown in the drawing, through the back contact of the armature 9 of the reverse code relay 6Y, front contact of the armature 7 of the normal code relay 6X, front contact of the armature 11 of the track relay 1TR, front 75 contact of the armature 12 of an approach locking relay LMR to be described later, wire 13, front contact of the armature 14 of a second approach locking relay RMR also to be described later, winding of the relay W, front contact of 80 the armature 8 of the relay 6X, back contact of the armature 10 of the relay 6Y and to the negative terminal C of the source of power. The polarity of the current supplied by this circuit is such as to position the armatures of the relay 85 W in the normal position, resulting thereby in the switch SM being set normal. It will be apparent from an inspection of the drawing that with the reverse code relay 6Y selected and the normal code relay 6X remaining deenergized, the current supplied by the above circuit to the relay W will be of reverse polarity thereby reversing the polarized armatures of the relay W and consequently positioning the switch SW in its reverse 90 position.

It will be understood however, that other means may be used to control the relay W such as for example, controllers operated by levers of a tower machine, without departing from the scope of our invention. The method shown in the drawing serves to illustrate all of the ways the switch may be controlled from a remote point.

The controllers 67, 73, and 78 are connected mechanically to the switch SW as indicated by a dotted line and are operated thereby. With the switch in its normal position, the controllers occupy an upper position in the drawing as indicated by the solid lines. With the switch in its reverse position, then the controllers 67 and 73 are shifted to a lower position as indicated by 110

the dotted lines in the drawing and 78 opens its circuit.

Traffic moving from the right to the left over the switch is governed by the signals L2A and

- 5 L2B. Traffic moving from the left to the right on the main track is governed by the signal R2A and traffic moving from the siding to the main track is governed by the signal R2B. These signals may be any of the standard types in general
10 use and are controlled in accordance to the usual practice by control relays designated in the drawing by the reference characters H with a prefix corresponding to the signal. The control relays R2AH and R2BH are themselves controlled by a directional relay RS as will shortly appear and the control relays L2AH and L2BH are controlled in a like manner by the directional relay LS. These directional relays RS and LS may themselves be controlled by means of
15 20 code relays selectively energized from a distant point such as the dispatcher's office or by controllers operated by levers of a tower machine or any other remote control system but as their control circuits form no part of our invention, they are omitted from the drawing.

- 25 The position of the signals R2A and R2B is checked by the relay RGP which is normally energized by a circuit that includes the controller 15 operated by the mechanism of the signal R2B and the controller 16 operated by the mechanism
30 35 of the signal R2A in series, and which controllers are closed only when their respective signals are in the stop position. In like manner, the normally energized relay LGP provides a check on the position of the signals L2A and L2B inasmuch as its energizing circuit includes the controller 17 operated by the signal L2B and the controller 18 operated by the signal L2A and which controllers are closed only when their respective signals are in the stop position.

- 40 Associated with each direction of traffic is an approach control relay and an approach locking relay. The approach control relay RAR associated with traffic from the left to the right is normally energized by a circuit that includes the front contact of the armature 19 of the track relay R2TR of the approach section R2T. The approach control relay LAR associated with traffic from the right to the left is normally energized by a circuit that includes front contact of the armature 20 of the track relay L2TR of the approach track section L2T.

- 45 The approach locking relay RMR associated with left to right traffic is normally energized by a stick circuit that extends from the positive terminal B through an armature 21 of the relay RGP, wire 22, front contact of its own armature 23, wire 24, winding of the relay RMR and to the negative terminal C. The pick-up circuit for the approach locking relay RMR extends from the same positive terminal B through the armature 21, to the wire 22 from which point there are provided three parallel paths, one of which includes the armature 25 of the approach control relay RAR, wire 26, switch controller 78, wires 79 and 29 connecting to the wire 24 which leads to the winding of the relay. A second parallel path for the pick-up circuit of RMR extends from wire 22 along wire 27, back contact of the armature 28 of the relay 1TR, and wire 29 connecting to the wire 24. The third parallel path extends from the wire 22 along wires 27 and 30, front contact of the armature 31 of a time element device TE to be described later and wires 32 and 29 to the wire 24.

The approach locking relay LMR associated with right to left traffic is normally energized by a stick circuit that extends from the positive terminal B through the armature 33 of the relay LGP, wire 34, front contact of its own armature 35, wire 36, winding of relay LMR and to the negative terminal C. The relay LMR is provided with a pick-up circuit that extends from the same positive terminal B through the armature 33 to the wire 34 from which point three parallel paths extend one of which includes a front contact of the armature 37 of the approach control relay LAR and to the wire 36, leading to the winding of the relay. The second parallel path extends from the wire 34 through a back contact of the armature 38 of the track relay ITR and to the wire 36, while the third parallel path extends from the wire 34 along the wire 39, front contact of the armature 40 of the time device TE and wire 41 to the wire 36.

Attention is here called to the fact that the control circuit previously traced for the switch control relay W includes the front contact of the armature 12 of the approach locking relay LMR and the front contact of the armature 14 of the approach locking relay RMR. It follows then that with either of the approach locking relays deenergized the control circuit for the relay W is open and no operation of the switch SW can take place.

Associated with the approach locking relays RMR and LMR is a time element device TE. This time element device TE may be any one of several types well known to the art. In this instance, it is a relay that brings its armatures into engagement with front contacts some predetermined time interval after the energizing circuit is closed. The time interval is of such duration that a train will be over the switch and gone or else will have had time to come to a stop to the rear of a signal. When traffic is from the left to the right in the drawing, the energizing circuit for the relay TE extends from the positive terminal B through the armature 21 of relay RGP, wire 22, armature 23 of the relay RMR when engaging its back contact, wire 53, winding of the relay TE and to the negative terminal C. When traffic is from the right to the left, the energizing circuit for the relay TE extends from the positive terminal B through the armature 33 of relay LGP, wire 34, armature 35 of relay LMR in engagement with its back contact, wires 54 and 53, winding of relay TE and to the negative terminal C.

A feature of our invention is to check the deenergized position of the approach locking relays to insure that a locked condition of the switch SW prevails before a proceed signal can be displayed to permit a train to move over the switch. This check is obtained by providing a special slow-releasing control relay MSP which relay controls the supply of current for clearing each of the several signals. The relay MSP is normally energized by a stick circuit that extends from the positive terminal B through the armature 42 of the relay RGP, wire 43, front contact of the armature 44 of the relay LGP, wire 45, front contact of its own armature 49, winding of the relay MSP and to the negative terminal C. The relay MSP is further provided with two holding circuits, one of which extends from the positive terminal B through a back contact of the armature 46 of the approach locking relay RMR, front contact of the armature 47 of the directional relay RS, wire 48, winding of the relay MSP and to the negative terminal C. The second holding circuit for the

relay MSP extends from the positive terminal B through a back contact of the armature 50 of the approach locking relay LMR, front contact of the armature 51 of the directional relay LS, wires 52 and 48, winding of the relay and to the negative terminal C.

The relay MSP also has a pick-up circuit that starts from positive terminal B and includes the back contact of the armature 76 of the directional relay RS, wire 77, back contact of the armature 51 of the other directional relay LS, wires 52 and 48, winding of the relay MSP and to negative terminal C. It follows that with either of the directional relays energized and its associated approach locking relay deenergized, so that both the pick-up circuit and the stick circuit are open, the control relay MSP is retained energized by a holding circuit. Also, the stick circuit will prevent relay MSP from being reenergized, once it has become deenergized after a directional relay has been selected, and the pick-up circuit reenergizes the relay in the event of its becoming deenergized for any reason under normal conditions. This control relay MSP controls the signal controlling circuits as will shortly appear.

The control of the H relays governing the signals R2A and R2B is by means of a circuit that extends from the positive terminal B through the armature 55 of the relay LGP, wire 56, back contact of the armature 57 of the opposing directional relay LS, wire 58, front contact of the armature 59 of the relay MSP, wire 60, front contact of the armature 61 of the track relay 1TR, wire 62, back contact of the armature 63 of the relay TE, wire 64, front contact of the armature 65 of the directional relay RS, wire 66, controller 67, wire 68 assuming the switch SW to be normal, winding of the relay R2AH and to the negative terminal C. In the event the switch is reversed so that the controller 67 occupies the position shown dotted in the drawing, then the circuit extends from controller 67 along the wire 69 to the relay R2BH and to the negative terminal C. The control circuit for the H relays that govern the signals L2A and L2B extends from the positive terminal B, through the front contact of the armature 70 of the relay RGP, wire 71, back contact of the armature 65 of the opposing directional relay RS, wire 64, armature 63, wire 62, armature 61, wire 60, front contact of the armature 59 of the relay MSP, wire 58, front contact of the armature 57 of the directional relay LS, wire 72, controller 73, wire 74, assuming the switch SW to be normal, winding of the relay L2AH and to the negative terminal C. In case the switch SW is reversed and the controller 73 occupies the position shown by the dotted line, then the circuit extends from controller 73 along wire 75, winding of the relay L2BH and to the common terminal C. As the control circuit for each of the H relays includes the front contact of the armature 59 of the relay MSP, it follows that no one of the signals can be cleared or retained in the proceed position unless the relay MSP is energized.

Let us assume that it is desired to advance a train past the switch on the main track from the left to the right. The selecting of the directional relay RS closes the circuit for the relay R2AH by the circuit traced above and the energizing of the relay R2AH results in the clearing of the signal R2A. As the signal R2A clears, the controller 16 operated by its mechanism is moved to open the circuit for the relay RGP and that relay becomes deenergized. As the relay RGP becomes deenergized, the normal

stick circuit to the control relay MSP is opened at the front contact of the armature 42 and that relay will become deenergized to release its armatures at the end of its slow-release period unless some other circuit is provided as its pick up circuit is also open at armature 76. The deenergizing of the relay RGP also opens the stick circuit of the approach locking relay RMR at the front contact of the armature 21. As the armature 21 is also included in each of the pick-up circuits of the relay RMR, it follows that relay RMR becomes deenergized when RGP is deenergized. As the directional relay RS is now up, the deenergizing of the approach locking relay RMR to bring its armature 46 into engagement with its back contact, closes a holding circuit to the relay MSP and thus relay MSP is retained energized. In the event that the approach locking relay RMR fails to open for any reason, then the holding circuit for the relay MSP is not closed and that relay becomes deenergized and its armatures drop at the end of its release period. With the relay MSP down, the circuit for the signal control relay R2AH is open at the front contact of the armature 59 resulting thereby in the signal R2A being set in the stop position. It follows that to clear the signal R2A to permit a train to move over the switch SW from the left to the right requires that the approach locking relay RMR must be deenergized and consequently an operation of the switch cannot take place, and that in the event the approach locking relay RMR fails to open the relay MSP functions to set the signal R2A in the stop position.

The selecting of the directional relay RS when the switch SW is reversed results in the signal relay R2BH being energized and the signal R2B being cleared to permit a train to move from the siding to the main track. As the signal R2B clears, the circuit to the relay RGP is opened at the controller 15 and the relay RGP becomes deenergized. The operation of the approach locking relay RMR and the relay MSP that follows the deenergizing of the relay RGP is identically the same as that just described when the signal R2A was cleared.

Again assume that the parts of the apparatus are in the position in which they are shown in the drawing and that it is desired to move a train from the right to the left on the main track. With the switch SW normal and the directional relay LS selected to raise its armatures to engage their front contacts, the closing of the front contact of the armature 57 closes the circuit to the signal control relay L2AH and the energizing of that relay clears the signal L2A. The clearing of the signal L2A opens the circuit to the relay LGP at the controller 18 and the deenergizing of the relay LGP opens the normal stick circuit to the relay MSP at the armature 44 and the stick circuit to the approach locking relay LMR at the armature 33. As the approach locking relay LMR becomes deenergized to close the back contact of its armature 50, the holding circuit for the relay MSP that includes the back contact of armature 50 and the front contact of the armature 51 of the relay LS is closed and thereby the relay MSP is retained energized. In the event the approach locking relay LMR fails to open, so as to close the holding circuit for relay MSP at back contact of armature 50, it follows that the relay MSP will become deenergized to open the control circuit of the relay L2AH at the front contact of its armature 59.

- In like manner, the deenergized position of the approach locking relay LMR is assured when traffic is directed from the right to the left with the switch SW reversed, as the clearing of the signal L2B opens the circuit to the relay LGP at the controller 17 to deenergize the relay LGP and thereby set up the same condition as described in connection with the clearing of the signal L2A.
- Again assuming that the apparatus occupies its normal position as shown in the drawing and that the directional relay LS is selected with the switch SW normal so that the signal L2A is cleared for traffic from the right to the left on the main track, if the train approaches and advances into the track section 1T to shunt the track relay 1TR, the circuit to the signal relay L2AH is opened at the armature 61 resulting thereby in the signal L2A being set at stop.
- As the signal L2A assumes the stop position, the relay LGP is reenergized and as the relay LGP picks up, the pick-up circuit for the approach locking relay LMR is closed at the armature 33 and at the back contact of the armature 38 of the relay 1TR. As the train advances to vacate the approach section L2T, the approach control relay LAR is reenergized and as the train advances to vacate the section 1T, the track relay 1TR picks up and the apparatus is restored to its normal condition.
- Assuming that after the signal L2A has been cleared and the train had advanced into the approach section L2T, it then became necessary to change the route, the dispatcher by deenergizing the relay LS will set the signal at stop and the relay LGP will be picked up. The approach locking relay LMR will remain however in its deenergized position. With relay LGP up and the relay LMR down, then the circuit is closed to the time element device TE and at the end of the predetermined time interval, the armature 40 of the relay TE will engage its front contact to close the pick-up circuit for the approach locking relay LMR and that relay is reenergized.
- After the relay LMR has become energized, then the switch control relay W can be operated in the usual manner. In a like manner, the apparatus functions for a train moving from the left to the right.
- Such apparatus as here described provides a positive check on the position of the approach locking relay, the utility of which will be apparent to all familiar with the art.
- Although we have herein shown and described only one form of apparatus embodying our invention, it is understood that various changes and modifications may be made therein within the scope of the appended claims without departing from the spirit and scope of our invention.
- Having thus described our invention, what we claim is:
1. In combination, a railway switch, a signal to govern traffic over said switch, a normally energized approach locking relay, means to govern the operation of said switch effective to move said switch only when said relay is energized, a signaling circuit adapted when closed to clear said signal, checking means rendered effective by the closing of said signaling circuit to deenergize said approach locking relay and to rupture said signaling circuit if said relay fails to release, and means responsive to the deenergizing of said relay to render said checking means ineffective to rupture said signaling circuit.
  2. In combination, a track section included in two different routes, a signal for each route to govern traffic through the section, an approach locking relay, means to select one or the other of said routes adaptable to select a route only when said approach locking relay is energized, a signal circuit for each signal adapted when closed to clear the signal, circuit means rendered effective by the closing of a signaling circuit to deenergize said approach locking relay and to rupture the closed signaling circuit if said relay fails to release, and means responsive to the deenergizing of said approach locking relay to retain the signaling circuit closed irrespective of said circuit means.
  3. In combination, a track section over which traffic moves in either direction, a signal at each end of the section to govern traffic in opposite directions through the section, an approach locking relay for each direction of traffic to control the section, a signaling circuit for each signal adapted when closed to clear the signal, a normally energized control relay, circuit means controlled by each signaling circuit and responsive to the clearing of a signal to deenergize the control relay and the associated approach locking relay, means responsive to the deenergizing of either approach locking relay to retain said control relay energized irrespective of said circuit means, and means controlled by said control relay to rupture said signal circuits upon the deenergizing of that relay.
  4. In combination, a track section including a track switch, a track circuit for said section, a signal to govern traffic through the section, a signaling circuit to control said signal adapted when closed to clear the signal, a normally energized approach locking relay provided with a stick circuit including a contact controlled by the signal, and a pick-up circuit including a contact closed upon the shunting of said track circuit, means to open the contact controlled by the signal upon the clearing of the signal to deenergize said approach locking relay, a normally energized control relay provided with a normally closed energizing circuit including a contact controlled by the signal, and a normally open holding circuit including a back contact of the approach locking relay, means to rupture said signaling circuit upon the deenergizing of said control relay, and means to govern the operation of the switch ineffective to move the switch as long as said approach locking relay is deenergized.
  5. In combination, a railway switch, a signal to govern traffic over the switch, a signaling circuit to control said signal adapted when closed to clear the signal, a normally energized approach locking relay provided with a circuit including a contact controlled by the signaling circuit, means to open said contact upon the closing of said signaling circuit to deenergize said relay, a control relay provided with a normally closed stick circuit including a contact controlled by said signaling circuit and a holding circuit including a back contact of the approach locking relay and arranged to be deenergized upon the closing of said signaling circuit unless the approach locking relay is deenergized to close the said back contact, means to rupture said signaling circuit upon the deenergizing of said control relay, and means to govern the operation of the switch ineffective to move the switch as long as said approach locking relay is deenergized.
  6. In combination, a railway switch, a signal to govern traffic over said switch, a directional relay

- adapted when energized to clear the signal, a normally energized approach locking relay adapted when deenergized to prevent operation of the switch; a normally energized control relay having a normally closed stick circuit, a holding circuit and a pick-up circuit; means rendered effective by the clearing of the signal to open said stick circuit, means responsive to the deenergizing of said approach locking relay to close said holding circuit, means responsive to the deenergizing of the directional relay to close said pick-up circuit, and means controlled by said control relay adapted to permit the clearing of said signal only when said control relay is energized.
- 5 8. In combination, a railway signal for governing traffic movements over a given stretch of track, a control relay for said signal, an approach locking relay, a circuit closed only if said signal indicates "stop" for energizing said approach locking relay, a circuit controlled by a front contact of said control relay for causing said signal to display a proceed indication, and means controlled by said control relay and by said approach locking relay for causing said signal to display a stop indication unless said approach locking relay closes its back contacts within a measured period of time after said signal ceases to display a stop indication. 80
- 10 9. In combination, a railway signal for governing traffic movements over a given stretch of track, a control relay for said signal, an approach locking relay, a circuit closed only if said signal indicates "stop" for energizing said approach locking relay, a checking relay, a circuit including a back contact of said approach locking relay and a front contact of said control relay for energizing said checking relay, a second circuit including a back contact of said control relay for energizing said checking relay, and a circuit including a front contact of said control relay and a front contact of said checking relay for causing said signal to display a proceed indication. 85
- 15 7. In combination, a railway track switch, a signal for governing traffic movements over said switch, an approach locking relay, a circuit for energizing said approach locking relay if and only if said signal is indicating "stop", a control relay for said signal, a slow release relay, a pick-up circuit for said slow release relay including a front contact of said control relay and a back contact of said approach locking relay, a stick circuit for said slow release relay energized if and only if said signal is indicating "stop", a second pick-up circuit for said slow release relay including a back contact of said control relay, a circuit including a front contact of said signal control relay and a front contact of said slow release relay for causing said signal to display a proceed indication, and a circuit controlled by said approach locking relay for controlling said switch. 90
